TELEPHONIC APPARATUS

Russell T. Kingsford, Wyncote, Pa., assignor to
Atwater Kent Manufacturing Company, Phila-
delphia, Pa., a corporation of Pennsylvania

Application May 17, 1930, Serial No. 453,129

6 Claims. (Cl. 179—115.5)

My invention relates to telephonic apparatus, particularly for loud-speaking purposes, comprising a diaphragm to which is attached a vibratory voice-current coil disposed in a magnetic field, produced either by a permanent, or, and preferably, by an electro-magnet.

In accordance with my invention, the lead or connection from the voice coil to the external circuit takes off to a fixed terminal directly from the coil-form or support, without attachment to and entirely independently of the diaphragm.

The lead or connection, which may be a continuation of the coil conductor itself or some other flexible lead attached to the coil conductor at or adjacent the coil-form or support, is attached at its outer end to a fixed binding post or terminal where movement or vibration of the lead is zero, while its inner end, attached to or substantially in fixed position with respect to the coil-form or support, moves or vibrates with an amplitude which is that of the vibrations of the coil and its support.

Further in accordance with my invention, when the vibratory diaphragm is of the conical or equivalent type of large diameter for direct action upon the air, the coil-form or support is attached thereto by any suitable means, and the anchorages or take-offs of the flexible coil leads are at points upon and fixed with relation to the coil support or form between the diaphragm and the coil, and for this purpose the coil-form or support is sufficiently long between the coil and diaphragm to permit full or maximum vibration of the coil without such close approach of the leads or their anchorages or take-offs to the pole structure of the magnetic field of the instrument as to cause the leads under any circumstances of use too closely to approach or contact with the pole structure.

My invention resides in structure, and in features of arrangement and proportionment, hereinafter described and claimed.

For an illustration of some of the various forms my invention may take, reference is to be had to the accompanying drawings, in which:

Fig. 1 is a vertical sectional view, partly in elevation, of loud speaking telephonic apparatus embodying my invention.

Fig. 2 is a vertical sectional view, on the line 2—2 of Fig. 2a, partly in elevation, of parts of Fig. 1, on enlarged scale.

Fig. 2a is a plan view of a spider or member effecting attachment of the diaphragm to the coil form or support.

Fig. 3 is a vertical sectional view on enlarged

scale, of a modified form of coil support or spool and its attachment to the diaphragm.

Fig. 4 is a sectional view of a diaphragm integral with the coil spool or form.

Fig. 5 is a fragmentary sectional view of a large 5 conical diaphragm and its actuating coil embodying my invention.

Fig. 6 is a vertical sectional view, parts in elevation, of a cone-type loud speaker embodying my invention;

Fig. 7 is a fragmentary elevational view on enlarged scale, partly in section, of a part of Fig. 6.

Fig. 7a is a vertical sectional view, parts in elevation, corresponding with Fig. 7, including a 15 binder tape for the leads.

Fig. 8 is a fragmentary diagrammatic view of an amplifier system utilizable for supplying sound-representing current to the voice coil.

Referring to Fig. 1, P is a pot or casing, of 20 cylindrical or other suitable formation, of iron or other suitable magnetic material, having a bottom 1 of like material in or to which is attached the central magnetizable core 2 terminating at its upper end in the cylindrical inner pole 25 piece I. Surrounding the pole 2 is the field or energizing coil C traversed by direct current, as from a storage battery, or by rectified alternating current, or equivalent. The leads 3, 4 from the terminals of the coil C extend to the exterior 30 of the pot P through the aperture 5 for connection to the exciting source.

The outer cylindrical surface of the pole I is one boundary of an air gap whose other boundary is the inner cylindrical surface of an aperture 35 in the outer magnetizable pole plate O secured to the pot by screws 6. In the air gap between the poles I and O is disposed the spool, support or form F upon which is wound the coil S, in one or more layers, traversed by sound-representing 40 current, the combination of the coil S with the magnetic field structure constituting an electrodynamic system. The coil form F of bakelite, paper, or other suitable material, is attached to the diaphragm D of mica, isinglass, metal or 45 other suitable material, by the member or spider Z of any suitable material such as sheet aluminum or other metal. Secured to the pole plate O by screws 7 is a dish-shaped plate 8 to which is secured by the screws 9 the cover plate 10 between 50 which and the plate 8 is a gasket 11 of rubber or other suitable material which holds the outer edge or periphery of the diaphragm D. Enclosing the diaphragm and its mounting is the member 55 12 of brass or the like, secured by screws 6, and

55 Fig. 3 is a vertical sectional view on enlarged

provided with a circular channel in which may be disposed a rubber tubing gasket 13 engaging the plate 10. In the member 12 above the diaphragm is a sound passage 14 with which registers the small end 15 of a horn or the like resting in a socket in the upper end of the member 12.

Referring more particularly to Figs. 2 and 2a, illustrative of parts comprised in Fig. 1, coil form F is shown as having a peripheral channel 10 in which is wound the voice coil S. The spider Z has a flange 16 extending outwardly from the cylindrical portion 17 fitting within the form F, and abutting against the end of the form. Extending upwardly and inwardly from the lower end of the cylindrical portion 17, the spider Z comprises the conical or equivalently shaped portion 18 having at its center a hole 19 through which the diaphragm D extends the rivet, screw or equivalent element 20 whereby the coil S is fixed to the diaphragm D for vibrating it in accordance with the sound-representing current traversing the coil. The portion 18 may be provided with one or more openings 21 to lighten the structure, and also facilitating application of the leads, as will now be described. Adjacent an opening 21 in the spider is a hole 22 extending through the wall of the form F adjacent the flange 16. There extends through this hole to the interior of the form F the lead L of any suitable conducting material such as a flexible or braided lead, solid wire or the like. On the inner end of the lead L is produced a head or enlargement 23 which, in the example illustrated, is a knot in the lead L. The enlargement 23 is larger than the hole 22, thereby preventing the lead L from pulling outwardly therethrough. Through a hole 24 one end of the conductor s, forming the winding S, is let into the interior of the form F, and then as indicated, the coil conductor s extends through the hole 22 to the exterior of form F and is there wrapped around the lead L and soldered thereto at 25 thus completing the anchorage of lead L. Suitable cement may be applied around the enlargement 23, or around the joint 25, or both, to prevent rattling of the lead L in the coil form F.

While, in the example illustrated, the lead L is not, in a structural sense, a continuation of the conductor of the coil S, it shall be understood that in all cases herein described, it may be. In the present example the conductor of the coil S may itself extend from the inside of the form F to the outside of the hole 22, and thence onwardly to the fixed terminal, and in this case, the hole 22 may be of smaller diameter, and again the conductor may be attached or anchored to the form F, either inside or outside, or both, or within the hole 22, by cement or equivalent.

By this form of take-off for the leads for connecting the coil S with the external circuit, the connection is entirely independent of contact with or attachment to the diaphragm D, and the inner end of the lead, at the form F, partakes of the same amplitude of vibration as that of the coil S due to the reaction of the sound-representing current passing therethrough upon the magnetic field of the air gap between the inner and outer poles I and O, Fig. 1.

In the example illustrated in Fig. 1, the leads L, preferably insulated, extend outwardly from the coil form through a slot or channel 8a on the under side of the plate 8, through an opening in the outer pole plate O, and thence through the aforesaid opening 5 in the pot P. Where the leads pass through the channel 8a they may be

individually covered by pieces of rubber or other tubing, not shown, which are held or clamped between the plate 8 and the pole plate O, and for the vibration of the coil S the leads between the form F and the inner end of the channel 8a flex or yield, their inner ends at or adjacent the coil form partaking of the same amplitude of movement as the coil itself.

In Fig. 3, the coil form F has the flange 26, preferably inwardly turned, held by rivets 20 to 10 the diaphragm D. Here again the form of lead attachment is that described in connection with Fig. 2, and the aforesaid cement is indicated at 27 as applied on the outside of the form F around the lead structure.

In Fig. 4, the diaphragm D has integrally formed therewith the coil form F. This may be done by moulding the structure of suitable material such as bakelite or the like, and, as indicated at the right, the diaphragm may be straight, 20 or, as indicated at the left, at 28, it may be grooved or channeled. Here again the lead attachment is generally that of the character described in connection with Figs. 2 and 3.

In Fig. 5, the diaphragm D, in conical or equivalent form, of paper, or other suitable material, is of large diameter for directly acting upon the air to produce sound waves therein. In this case the lead structure is generally of the character of that hereinabove described. To the coil form F, at a region above the hole 22, the diaphragm is attached by a resilient spider structure Z of sheet aluminum or the like, between whose cylindrical portion 17 and the exterior of the form F is held the inwardly turned cylindrical flange 35 of and at the inner end of the cone D, the latter overlying the outwardly turned flange 17a of the spider structure. The spider Z in this case is of a character for securing it at its center to an extension on the inner pole piece generally of 40 the character disclosed in Fig. 6. While the outer pole plate O is shown with its central cylindrical aperture forming a boundary of the air gap, the inner pole piece I is omitted for the sake of clearness.

In Fig. 6 is shown a cone-type loud speaker embodying my invention. The field producing means again comprises the pot P, core 2, inner and outer pole pieces I and O and exciting coil C. The bolts or screws 29 secure the outer pole plate O and the housing 30 for the cone D to each other, and secure the pole plate O on the end of the pot P. The housing 30 has at its outer and forward end a ring 31 in a channel in which is held the outer flange of the member 32 of cloth or similar material glued to the outer end of the cone D. Overlying the aforesaid flange of the member 32 is the metal or other washer 33 held to the ring 31 by the screws or rivets 34. Overlying the washer 33 and ring 31 is a felt or other suitable washer or ring 35 which may press against a wall of a cabinet with the diaphragm D in register with the sound opening thereof.

The coil form F is secured to the diaphragm D by a spring spider Z of the character illustrated in Fig. 5. At its center the spider Z is secured by screw 36 to the tip 37 on the outer end of inner pole piece I. The leads L are secured at their outer ends to the fixed terminals or binding posts 38 carried upon insulating block 39 secured to the housing 30, and from these binding posts extend the conductors 40 to the source of sound-representing current. In this example of my invention, as more clearly apparent from Fig. 7, leads take off from points 41 on the coil 75

form F, where the leads may be anchored or attached by cement or otherwise. Or, and preferably, as indicated in Fig. 7a the leads at the point of take-off are held firmly to or anchored against the form F by cloth or adhesive tape 42 which, in the portions which extend over the extreme inner end of the cone D, may be slotted as indicated at 43, to permit ready application around the leads. The leads from the binding posts 38 to the points 41 may be of braided or other flexible conductor, or they may in fact be integral continuations of the coil conductor's itself. As indicated in Figs. 7 and 7a, the neck 44 of the form F between the upper end of the coil S and the lower end of the cone D is sufficiently long that the points of attachment or anchorages as 41, Fig. 7, or within the lower portion of the tape 42, Fig. 7a, will not, at the greatest amplitude of vibration of the coil S, bring the inner portions 20 of the leads L near or into contact with the outer pole structure O or any other structure necessarily adjacent thereto.

In all the arrangements described, and in similar and equivalent arrangements comprehended in my invention, the take-off of the voice coil leads is entirely independent of the diaphragm, whatever its form, and is directly from the voice coil or its form; and the inner ends of the leads at or adjacent the coil or its form partake of an 30 amplitude of vibration which is equal to the amplitude of the vibration of the coil itself, as contrasted with prior structures of microphones and coil actuated diaphragms, in which the leads to the external circuit are attached to the diaphragm and take off to fixed terminals or binding posts from a region on the diaphragm whose amplitude of vibration is less than at or adjacent its center where the microphonic elements or coil is disposed.

40 An electro-dynamic system of the general character herein described is effective for producing sound waves of large amplitude when the sound-representing current traversing the voice coil is of sufficient magnitude. This is accomplished by any suitable means, especially audio frequency amplification by valves of the audion type. Such an arrangement, used by me and commonly in use, is indicated in Fig. 8 where V is a vacuum tube of the three electrode type 45 utilized as an audio frequency amplifier upon whose input electrodes is impressed by the transformer T a sound-representing voltage derived from any source, particularly from a prior stage or stages of audio frequency amplification. As 50 usual, the tubes, of which V is one, have their filaments or cathodes excited by current from the source A and their anode or plate circuits supplied by current from the source B. The plate circuit of the tube V is coupled to the voice coil 55 S by the second audio frequency transformer T1, which in an arrangement of the character indicated, is generally a step-down transformer.

What I claim is:

1. In telephonic apparatus of the character described, the combination with a diaphragm, of a

coil form, a member attaching said form to said diaphragm, a voice coil on said form, a connection from said coil extending into the interior and thence to the exterior of said form, and extending therefrom independently of said diaphragm and said attaching member to a fixed point. 5

2. In telephonic apparatus of the character described, the combination with a conical diaphragm of large diameter, of a coil form secured thereto, a voice coil on said form, a lead taking off from said form and extending independently of said diaphragm to the external circuit, and sheet material anchoring the lead to said coil form at a point between said coil and said diaphragm and overlying the adjacent end of said diaphragm. 10 15

3. In telephonic apparatus of the character described, the combination with a conical diaphragm of large diameter, of a coil form secured thereto, a voice coil on said form, a lead taking off from said form and extending independently of said diaphragm to the external circuit, and sheet material anchoring the lead to said coil form at a point between said coil and said diaphragm and overlying the adjacent end of said diaphragm, said sheet material having a slot 20 25 extending from its remote edge to the lead adjacent its take-off from said coil form.

4. In telephonic apparatus of the character described, the combination with a conical diaphragm of large diameter, of a coil form secured thereto, a voice coil on said form, a lead from said coil, and sheet material anchoring the lead to said coil form at a point between said coil and said diaphragm, said lead extending independently of said diaphragm to the external circuit. 30 35

5. In telephonic apparatus of the character described, the combination with a conical diaphragm of large diameter, of a voice coil for actuating the same, a form on which said voice coil is disposed and which extends at substantially the diameter of said coil to said diaphragm, a member attaching said form adjacent its one end to said diaphragm, a lead extending on the outer side of said form from said coil towards said diaphragm and taking off from said form and flexibly extending independently of said diaphragm and said attaching member to the external circuit, and means defining the point of take-off of 40 45 50 said lead comprising means anchoring said lead on the outer side of said coil form at a point between said coil and said end of said coil form.

6. In telephonic apparatus, the combination with a diaphragm, of a coil form, a voice coil on said form, a field pole plate and a pole spaced therefrom to form an air gap in which said voice coil vibrates, a spider, said coil form, spider and diaphragm united to each other, a flexible lead for connecting said coil to the external circuit, and an anchorage for said lead comprising means securing it to said coil form independently of said spider for take off of said lead independently of said spider and said diaphragm. 55 60 65

RUSSELL T. KINGSFORD. 65
